(57) **CLAIM**

The ornamental design for LED-lighted luggage, as shown and described.

DESCRIPTION

FIG. 1 is a perspective view of the LED-lighted luggage;
FIG. 2 is a front view of the LED-lighted luggage shown in FIG. 1, with the rear side being identical;
FIG. 3 a side view of the LED-lighted luggage shown in FIG. 1, with the opposite side being identical; and,
FIG. 4 is a top view of the LED-lighted luggage shown in FIG. 1.

The broken lines showing portions of luggage are for the purposes of illustrating environment and form no part of the claimed design.
